UNITED STATES PATENT OFFICE.

BURNSIDE ELLSWORTH SAWYER, OF FITCHBURG, MASSACHUSETTS.

GOLF-BALL TEE OR SUPPORT.

Application filed September 8, 1924. Serial No. 736,511.

To all whom it may concern:

Be it known that I, BURNSIDE ELLSWORTH SAWYER, a citizen of the United States, residing at Fitchburg, in the county of Worcester and State of Massachusetts, have invented certain new and useful Improvements in Golf-Ball Tees or Supports, of which the following is a specification.

This invention relates to teeing a ball on the tees of a golf course. The principal objects of this invention is to provide means by which a ball can be supported at a predetermined height from the ground, so that when the ball is driven from this support, it will not retard or deflect it; and if the stroke of the club is too low, the supporting member will collapse, and at the same time deflect the club to a more correct position for a proper shot. Another advantage of this invention is that this supporting member is so resilient, and its composition of such a character, that instead of being driven away by the force of the stroke, it simply collapses and stays on or near its original position.

To simplify the description, I will hereafter call this supporting member, a tee.

Reference is to be had to the accompanying drawings, in which—

Fig. 1 is a plan view of the tee;
30 Fig. 2 is a side view of the tee supporting a ball;

Fig. 3 is a face view of Fig. 2;

Fig. 4 is a plan view showing position of tee when collapsed under the force of a 35 drive; and

Fig. 5 is a side view of Fig. 4, showing relative position of collapsed tee to the ball.

In the drawings I have shown a preference for a tee of conical shape. It is apparent that anyone skilled in the art, could 40 make the supporting walls with a concave or convex surface, also irregular in shape, without departing from the scope of my invention. I do not wish to be limited to the size, shape, or number of serrations in the wall 45 of the tee, but what I do claim is:—

1. A golf tee made of thin resilient material having a hole or depression at apex suitable to support a golf ball and a cut or opening extending through one side wall to 50 the center.

2. A golf tee having an opening at its top suitable to support a golf ball with a cut through the side wall into this opening and made of a resilient material that will cause 55 it to assume its original shape after being forced to a horizontal plane when the pressure is removed.

3. A golf tee made of thin resilient material having a hole or depression at apex 60 suitable to support a golf ball and a cut or opening extending through one side wall to the center; the wall of said tee to be at such an angle to the horizontal plane that when the driving club strikes this wall, it will 65 collapse the tee, and slide over it without projecting it with the ball.

BURNSIDE ELLSWORTH SAWYER.
